UNITED STATES PATENT OFFICE.

SANDER I. CHRISTENSEN, OF WILLOWS, CALIFORNIA.

AUTOMOBILE HEADLIGHT.

Application filed August 14, 1922. Serial No. 581,573.

To all whom it may concern:

Be it known that I, SANDER I. CHRISTENSEN, a citizen of Denmark, residing at Willows, in the county of Glenn, State of California, have invented a new and useful Automobile Headlight, of which the following is a specification, in such full and clear terms as will enable those skilled in the art to construct and use the same.

This invention relates to a head light for automobiles, and its object is to produce a head light which will adequately illuminate the road and which will comply with the law with respect to reducing the glare to prevent the blinding of approaching drivers.

It will be understood by those skilled in the art that with the ordinary head lights, it is very difficult to prevent drivers approaching an automobile from being so blinded by the head lights as to interfere with them and make accidents likely to happen.

With the present invention a reflector is used, which is provided with a silvered surface adapted to scatter the light sufficiently to illuminate the road on all sides, but which reflector is provided with a dull reflecting surface at the center to prevent approaching drivers from being blinded.

Other objects of the invention will appear as the description proceeds.

An embodiment of the invention is shown in the accompanying drawings in which the same reference numeral is applied to the same portion throughout.

Fig. 1 is a side elevation partly in section of the complete lamp.

Fig. 2 is a back view of the lamp showing the manner of supporting it and showing the means for securing the reflector and reflector cover in place.

Fig. 3 is a front elevation of the reflector.

Fig. 4 is a plan view of the ring for retaining the reflector and glass cover in place.

Fig. 5 is a view of one form of the reflector in which the upper portion of the lamp is provided with a smaller amount of mirror surface than is shown in Figure 3, the object being to break up the rays of light from the upper portion of the reflector more than the reflector in Figure 3 will do.

Fig. 6 is a view, partly in section of a form of the lamp in which the light globe is carried by the glass cover.

The reflector consists of a suitable body of metal or glass convex outwardly as indicated at 1, which has a socket 2 placed at its center to carry the ordinary electric globe 3. This reflector is supported by a flat plate 4, said flat plate having two supporting ears 5 and 6 to connect it to the ordinary lamp supporting yokes, in a manner well known in the art. The plate 4 has pins 7 and 8 which are for the purpose of securing the cover retaining ring 9 in place. This ring has bayonet joined slots 10 on opposite sides thereof with which the pins 7 and 8 are engaged to secure said ring in place.

The retaining ring bears upon a bead 11 on the outer rim of the semi-spherical glass cover 12, said cover also bearing upon the outer periphery of the reflector 1, and thereby holding it in place.

It will be seen in observing Figures 3 to 5 that the lower portion of the reflector is silvered and the upper portion is silvered over only a portion of its upper area, the center of said reflector being painted with a dull enamel such as aluminum paint or something of that character, to reflect the light without causing the formation of blinding rays, such as are reflected from the ordinary silvered surface.

Where less light is desired to be reflected from the upper portion of the reflector, lines or a word or letters covering a portion only of the reflector may be silvered as indicated at the upper portion of Figure 5, the lower portion of the reflector being also silvered, and the central portion being covered with a dimly reflecting enamel.

While the lamp has been shown in Figures 1 to 5 as being carried by the reflector itself, it is equally possible to secure the lamp to the glass cover as indicated in Figure 6.

In this figure the lamp back is indicated at 20, the convex reflector at 21, which reflector is silvered in substantially the same manner as the reflector shown in Figure 3; the semi-spherical glass cover 22 is secured in place by means of a ring 23 in substantially the same manner as the ring 9 is secured to the pins 7 and 8, pins 24, 25 being used for this purpose. At the front of the semi-spherical cover it has a lamp socket, in which is placed the lamp 27.

In operation it will be seen that the light from the lamp, in either form of the inven-

tion, will strike the convex reflector in such a manner as to be reflected downwardly upon the road, substantially none of it from the lower portion of the reflector being reflected into the eyes of the on-coming driver. Whatever strikes the upper portion of the reflector will be reflected onto the sides of the road, or above the view of the approaching driver so as to not interfere with him 10 in any degree.

What I claim is as follows, but various modifications may be made in the construction shown in the drawings and above particularly described form, within the pur- 15 view of my invention.

An automobile head light comprising a flat supporting plate, a convex reflector carried thereby, said reflector having its lower portion silvered and having silvering on a portion of its upper portion, the central portion of said reflector being treated to make it dimly reflecting, a lamp placed to illuminate said reflector, a transparent convex cover adapted to enclose said lamp and the reflector and a retaining ring for securing said cover to said support. 20 25

In testimony whereof I have hereunto set my hand this 5th day of August A. D. 1922.

SANDER I. CHRISTENSEN.
